US00D510193S

(12) United States Design Patent (10) Patent No.: US D510,193 S
(45) Date of Patent: * Oct. 4, 2005

(54) WOVEN FABRIC

(75) Inventor: Olga Bellver Lopez, San Juan -
Alicante (ES)

(73) Assignee: Albambra International, SA, Alicante
(ES)

() Term: 14 Years

(21) Appl. No.: 29/214,473

(22) Filed: Oct. 5, 2004

(51) LOC (8) Cl. 05-05

(52) U.S. Cl. D5/37
